UNITED STATES PATENT OFFICE.

ARVID LIND, OF STOCKHOLM, SWEDEN.

INTERNAL-COMBUSTION ENGINE.

Application filed May 14, 1922, Serial No. 638,889, and in Sweden May 18, 1922.

This invention relates to improvements in internal combustion engines.

Internal combustion engines of the two-stroke type are known, which have a central shaft and a plurality of cylinders the axes of which are parallel to said shaft and the pistons of which are connected to a gyroscopically swinging thrust disc journaled on an oblique hub secured to the shaft the cylinder chambers on one side of the pistons forming working chambers and the chambers in the opposite side of the pistons serving as pumping chambers wherein the explosive mixture is drawn in and precompressed, prior to its introduction into the working chambers.

The object of this invention is to provide an internal combustion engine of the above stated kind which is of a simple and compact construction and efficient in operation and in which the explosive mixture is formed and introduced in the different cylinders in a very regular manner.

The invention consists, chiefly in the combination with an engine of the type set forth of a common charge forming chamber having a carburetting device, a common storing chamber for the charge formed, and a distributing rotary valve secured to the shaft and adapted in the operation of the engine successively to control the introduction of the charge into the pumping chambers of the engine and its supply to the storing chamber from said pumping chamber.

The invention is illustrated in the accompanying drawing, in which, Figure 1 is a central longitudinal section of one embodiment of an internal combustion engine in accordance with the present invention. Fig. 2 is a corresponding section of the distributing valve at right angles to the shaft. Fig. 3 is a cross-section of the engine taken at right angles to the shaft along the line A—B—C—D in Fig. 1. Fig. 4 is a central longitudinal section taken at right angles to the section shown in Fig. 1. Fig. 5 is a corresponding section of the distributing valve. Fig. 6 is a central longitudinal section of the engine taken half-way between the sections shown in Figs. 1 and 4. Fig. 7 is a corresponding central cross-section of the engine. Fig. 8 is a cross-section of another embodiment having a conical distributing slide valve. Fig. 9 represents a section thereof taken along the line 9—9, Fig. 8. Fig. 10 is

another section thereof taken along the line 10—10, Fig. 8.

The casing of the engine is preferably divided in two parts along a plane at right angles to the shaft substantially half-way between its ends, one part 1 of the casing containing borings forming the working chambers 2 of the cylinders, while the other part 3 contains borings forming corresponding pumping chambers 4 for the charge. The number of cylinders is four in the example shown, but may be larger or smaller according to the circumstances. A driving shaft 5 is journaled centrally in the casing and the cylinders are placed parallel to said shaft and uniformly distributed around the same.

A hub 6 is secured to the shaft 5 in an oblique position and carries an obliquely mounted driving disc 7, journaled by means of ball bearings 8, so as to permit the hub secured to the shaft to rotate relatively to the driving disc while the latter performs a gyroscopically swinging movement. Each cylinder contains a piston 9 connected at a point substantially half-way between its ends to the driving disc 7 by means of a ball and socket joint consisting of a perforated ball 10 placed on a pin extending from the disc 7 and a sliding block 11 mounted in the piston to enable the radial and lateral movements performed by the ball 10 in relation to the pistons in the operation of the engine. To prevent the driving disc from rotating with the hub or thrust block 6 and the shaft the driving disc is provided with two diametrically opposed guiding pins 12 (or one such pin only) positioned in an axial plane between the cylinders and provided with sliding blocks 13 engaging axial guiding slots formed in the casing of the engine. The same effect may also be obtained by carrying out two diametrically opposed ball and socket joints (or one such joint only) of the pistons in such manner that they can move in the radial direction only but not in the peripheral direction relatively to the pistons. To prevent the pistons from rotation within the cylinders the pistons are provided with extensions 14 sliding in corresponding slots 15 formed in the casing of the engine.

A charge forming chamber 16 is provided between two pumping chambers having air inlet passages 17 and a carburetting device to supply liquid fuel (as gasoline, spirit,

petroleum or the like) to the air. The carburetting device is shown in the drawing as a supply pipe 18 having an injection channel, it should be noted, however, that 5 any known type of carburettor may be used through which the air passes and is loaded by the fuel. A rotary slide valve 19 secured to the shaft outside the ends of the pumping chambers of the cylinders controls 10 the introduction of the air into the pumping chambers of the cylinders and its transmission into a storing chamber 20 formed in the middle portion of the casing and enclosing the driving disc, the carburetted 15 and slightly compressed air being stored in said chamber before entering the working chamber of the cylinders. To this end the said slide valve is formed with a passage 21 by means of which the pumping chambers 20 of the cylinders may be successively connected to the charge forming chamber 16 during the suction stroke by way of an 25 annular passage 22 formed in the end surface of the cylinder casing and an opening 23 formed in the bottom of the pumping chamber, the slide valve having further a passage 24 whereby the pumping chambers may be successively connected to the storing chamber 20 during the precompression 30 stroke by way of the opening 23 and an annular passage 25 formed in the end surface of the casing. The slide valve has also a passage 26 whereby fresh air may be drawn directly into the pumping chambers of the 35 cylinders. To secure an effective tightening the slide valve 19 is constantly pressed against the end surface of the cylinder casing by a resilient washer 27. The cylinders are provided in the usual way with sparking 40 plugs 28 and the charge is taken in from the storing chamber 20 through ports 29 formed in the cylinder walls and controlled by the pistons, while the combustion gases are expelled through ports 30 likewise 45 controlled by the pistons in the way commonly used in two cycle engines.

The operation of the engine will now be described in connection with one cylinder, the remaining cylinders operating in the 50 same way with the time interval determined by the connection of their pistons to different points of the driving disc. When the pistons are moved to the left due to the pressure of explosion driving power is imparted to the driving disc 7 which is caused to perform a gyratory, swinging movement translated into a rotation of the hub 6 and the shaft 5 in well-known manner. In the 55 position of the lower piston 9 shown in Fig. 1 the expansion has been completed within the working chamber of the respective cylinder and the combustion gases have been expelled through port 30, while a fresh charge of carburetted air has at the same 60 time entered the working chamber of the 65

cylinder. At the same time the carburetted air compressed in the corresponding pumping chamber has been forced through port 23, passage 24 in the slide valve 19, and passage 25 in the rear wall of the casing 70 into the storing chamber 20. Upon the subsequent reversal of the piston and the movement thereof to the left the charge will be compressed in the usual way within the working chamber of the cylinder and 75 ignited at the end of the compression period. During this period the slide valve 19 is rotated so much that the slide valve channel 21 connects the pumping chamber 4 to the charge forming chamber 16 during a part 80 of the suction stroke of the piston. To obtain an effective carburation preheated air is preferably used in which case the engine may also be driven by heavy fuels such as spirit or kerosene. Towards the end of the 85 suction stroke the pumping chamber 4 will be directly connected to the atmosphere through the slide valve passage 26 so as to draw in cold fresh air to dilute the carburetted air previously drawn in and lower 90 its temperature. When ignition has taken place in the working chamber of the cylinder and the piston has initiated its movement from its extreme left hand position towards the right the combustion gases expand in the working chamber of the cylinder while the charge drawn into the pumping chamber will be forced through port 23 passage 24, and passage 25 into the storing chamber 20 whereupon the operation described is repeated. 100

The embodiment according to Figs. 8-10 differs from that above described substantially only by that the distributing slide valve 19 secured to the shaft 5 is conical and covered by a disc 31 attached to the cylinder casing, said disc being formed with ports 32 cooperating with the slide valve passage 26 in the direct suction of air into the cylinders. The passages of the slide 105 valve 19 are designed substantially in the same way as those illustrated in Figs. 1-7 with the differences determined by the conical shape of the valve.

It is evident that the details of the engine 110 may be varied in many ways without departing from the principle of the invention.

What I claim is:—

1. An internal combustion engine comprising a plurality of cylinders, a piston in each cylinder forming a working chamber and a pumping chamber in the cylinder, a charge forming chamber, a carburetting device connected with the latter, a storing chamber common to all the working and pumping chambers, and a rotary valve adapted to control the introduction of a charge from the charge forming chamber successively into the pumping chambers and from the latter into the common storing chamber. 115

2. An internal combustion engine of the two-cycle type, comprising a shaft, a group of cylinders arranged axially around said shaft and having working and pumping chambers, pistons in said cylinders, an oblique hub on said shaft, a driving disc journalled on said hub and engaging said pistons, a central storing chamber for carburetted air enclosing said driving disc, a charge forming chamber, a carburetting device, and a rotary valve secured to the shaft and adapted to control the introduction of the charge into the pumping chambers of the cylinders and its supply to the storing chamber.
3. An internal combustion engine of the two-stroke type comprising a stationary case, a revoluble shaft, journalled in said case, a group of cylinders in said case arranged axially around the shaft and having working chambers and pumping chambers, pistons in said cylinders, a wabbling disc journalled in an oblique position on said shaft and engaging said pistons, a charge forming chamber common to the cylinders, a storing chamber common to the cylinders, and a rotary valve adapted to control the introduction of the charge from the charge forming chamber into the pumping chambers of the cylinders and its supply to the storing chamber from said pumping chambers.
4. An internal combustion engine of the two-stroke type, comprising a stationary case, a revoluble shaft journalled in said case, a group of cylinders in said case, arranged axially around the shaft and having working chambers and pumping chambers, pistons in said cylinders, a wabbling disc journalled in an oblique position on said shaft and engaging said pistons, a charge forming chamber common to all cylinders, a rotary valve adapted to connect said charge forming chamber with the pumping chambers of the cylinders in succession and with the open air at the end of the suction stroke, and a storing chamber for the charge adapted to be connected in succession with the pumping chambers for receiving the charge delivered from the latter before its entrance into the working chambers of the cylinders.

5. An internal combustion engine of the two stroke type, comprising a stationary case, a revoluble shaft journalled in said case, a group of cylinders in said case arranged axially around the shaft and having working chambers and pumping chambers, pistons in said cylinders, a wabbling disc journalled in an oblique position on said shaft and engaging said pistons, a charge forming chamber common to all cylinders, a rotary valve adapted to connect said charge forming chamber with the pumping chambers of the cylinder in succession, a central storing chamber for the charge adapted to be connected in succession with the pumping chambers for receiving the charge delivered from the latter before its entrance into the working chambers of the cylinders, said storing chamber also enclosing the wabbling disc.

In testimony whereof I have signed my name.

ARVID LIND.
